UNITED STATES PATENT OFFICE

WALTER J. VAN ROSSEM, OF LOS ANGELES, CALIFORNIA, ASSIGNOR TO SURGIDENT, LTD., OF LOS ANGELES, CALIFORNIA, A CORPORATION OF CALIFORNIA

SANITARY COVERED RECEPTACLE

Application filed August 29, 1931. Serial No. 560,123.

This invention relates to a covered receptacle, and while features of the invention may be applied for securing a cover to a receptacle of any kind, the invention is particularly useful in the construction of a sanitary receptacle in which the cover can be removed so as to enable the receptacle to be sterilized or cleaned. Figure 3 is a view taken about on the line 3-3 of Figure 1 with the lower part of the receptacle broken away.

Figure 4 is a view showing in detail and upon an enlarged scale the latching means on the side wall of the receptacle. The view is a horizontal section.

The general object of the invention is to produce a receptacle having a detachable cover which can be readily applied to the receptacle so as to become latched thereto but which, when desired, can be readily disengaged from the receptacle.

15 A further object of the invention is to provide a covered receptacle including a flanged cover having a body section and to provide the body section and the receptacle with interlocking means to enable the cover section to be latched to the receptacle by sliding the same into place on the upper edge of the wall of the receptacle.

Further objects of the invention will appear hereinafter.

25 The invention consists in the novel parts and combinations of parts to be described hereinafter, all of which contribute to produce an efficient sanitary covered receptacle.

A preferred embodiment of the invention is described in the following specification, while the broad scope of the invention is pointed out in the appended claims.

In the drawing:

Figure 1 is a plan of a covered receptacle embodying my invention, a portion of the cover being broken away so as to show the wall of the receptacle in cross section, and likewise a portion of the flange of the body section of the cover.

40 Figure 2 is a side elevation of the receptacle and cover partially broken away so as to show a portion of the wall of the receptacle in cross section together with a portion of the cover.

45 Figure 3 is a vertical section through the

receptacle and cover taken about on the line 3-3 of Figure 1 with the lower part of the receptacle broken away.

Figure 4 is a view showing in detail and upon an enlarged scale the latching means on the side wall of the receptacle. The view is a horizontal section.

Figure 5 is a side elevation of a portion of the flange of the body section of the cover illustrating details of the construction.

55 Figure 6 is a side elevation showing a portion of a receptacle and illustrating another embodiment of the invention, certain parts being broken away, and showing the body section of the cover being put in place.

60 In practicing the invention, I prefer to employ a receptacle of glass and make a cover of metal, preferably sheet metal. The cover is preferably constructed in two pieces, namely, a body section and a movable lid or cover section attached to the body section of the cover. The body section of the cover is constructed with a marginal flange and is adapted to be latched in place on the upper edge of the wall of the receptacle to prevent it from being moved laterally off the receptacle. The wall of the receptacle and the flange of the body section are provided with interlocking means to latch the body section of the cover in place.

75 The interlocking means carried by the body section of the cover is preferably resilient and cooperates with the receptacle wall so that when desired the cover can readily be slid off of the receptacle.

80 Referring more particularly to the parts, 1 indicates a receptacle preferably made of glass or other material which can readily be sterilized by heat or other means, and this receptacle is preferably of box form comprising side walls 2 and end walls such as the end wall 3 (see Figure 1). The cover includes a body section 4 which preferably carries a movable cover section 5. The body section 4 is provided with a marginal flange 6 in-

cluding side extensions 7 which extend parallel with the direction of sliding the body section into place as indicated by the arrow in Figure 1, and the flange also includes an end extension or end flange 8.

On the side flanges 7 I provide locking means preferably in the form of dogs which project inwardly and are received in sockets 9 formed in the outer face of the walls 2 near their upper edge, and these dogs are preferably in the form of pins 10 having rounded heads disposed on the inside of the flange.

I prefer to provide resilient means for urging these dogs or pins inwardly so as to snap them into the sockets 9 after the body section 4 has been slid into place. For this purpose I provide either a spring corresponding to each pin or a double spring 11 which is in the form of a bar secured by a rivet 12 to the middle portion of the end flange 8, and this spring has side arms 13 which extend along the inner sides of the side flanges 7 and engage under the heads of the pins 10 so as to urge them inwardly. In order to increase the spring effect, these side arms 13 of the spring may each be provided with a bend or small spring bow 14 (see Figure 1).

In order to guide the heads of the pins 10 into the sockets 9, I prefer to provide each side wall near its upper edge with a guide groove 15. The sockets 9 are slightly deeper than the grooves 15 so as to form a rudimentary shoulder 16 to enable the sockets to yieldingly retain the pins.

The end wall 3 of the receptacle and the end flange 8 of the body section are also preferably provided with interlocking means to prevent this edge of the body section 4 from being raised from the adjacent end wall 3. For this purpose I provide a socket 17 in the outer face of the end wall that receives the inner head of the pin or rivet 12.

I prefer to utilize the pins 10 as pivots for attaching the movable cover section 5. For this purpose, the cover section 5 is provided with a flange 18 which is formed with integral extensions or ears 19 which have perforations to receive the pins.

The side flanges 7 are formed with openings 18 into which the pins 10 pass and these openings are preferably elongated in a horizontal direction. This is important because it prevents any strains being developed in the glass which might break the same when the article is subjected to changes in temperature. The end of each flange 18 of the cover section 5 is provided with an opening or eye 20 which fits closely to the side of the pin 10 so as to operate as an efficient hinge joint.

In Figure 6 I illustrate another embodiment of the invention in which the body section 21 of the cover may be applied by snapping it down into place instead of sliding it into place as in the other embodiment of the invention already described. In this em-

bodiment shown in Figure 6, the construction of the cover section 21 is the same as before, but instead of having a guide groove at each side of the receptacle 22, I provide a socket 23 similar to the socket 17 (see Figure 1) to receive a projection or pin 24 similar to the rivet 12. Each side of the receptacle is provided with a socket 25 extending down from the upper edge 26 of the wall and provided with a rounded horizontal shoulder 27. The cover should be applied as indicated in Figure 6 so that the pin 24 engages the socket 23, and then the cover section is swung downwardly so that the heads of the pins 28 will pass into the sockets 25.

In this way, they snap under the shoulders 27 through the agency of their springs 29 which correspond to the springs 13.

When it is desired to sterilize the cover, it may be removed from the receptacle and then the two sections disengaged by shoving the pins 10 or 28 outwardly.

It is understood that the embodiment of the invention described herein is only one of the many embodiments this invention may take, and I do not wish to be limited in the practice of the invention, nor in the claims, to the particular embodiment set forth.

What I claim is:

1. In a covered receptacle, the combination of a receptacle body of substantially rectangular form having an upper opening with a wall extending around the said opening, a cover having a body section capable of being placed over the edge of the wall at one side of the receptacle so as to cover a part of the said opening toward one end of the receptacle, cooperating means on two opposite walls and the said body section for latching the body section against being moved laterally off the receptacle, and cooperating means on a transverse wall and the body section for latching the same against being raised off the wall, and a movable cover section carried by the body section of said cover, for covering the remainder of the opening.

2. In a covered receptacle, the combination of a receptacle body having an upper opening with two parallel side walls and two transverse end walls extending around the said opening, a cover having a body section capable of being placed over the edge of the wall at one side of the receptacle so as to cover a part of the said opening, said body section having a marginal flange with yielding means movably mounted on the flange and projecting inwardly at two opposite points on the flange, and said side walls having means on their outer faces to cooperate with said last named means to latch the body section against lateral movement along the side walls, and means for interlocking the transverse portion of the flange with the adjacent transverse wall of the receptacle body.

3. In a covered receptacle, the combination

- of a receptacle body having an upper opening with a wall extending around the said opening, a cover having a body section capable of being slid laterally over the edge of the wall at one side of the receptacle so as to cover a part of the said opening, said body section having a marginal flange with means projecting inwardly, said wall having means on its outer face to cooperate with said last named means to latch the body section against lateral movement off of the receptacle body, and a movable cover section carried by the body section of said cover.
4. In a covered receptacle, the combination of a receptacle body having an upper opening with a wall extending around the said opening, a cover having a body section capable of being slid laterally over the edge of the wall at one side of the receptacle so as to cover a part of the said opening, said body section having a marginal flange including side extensions lying substantially parallel with the direction in which the body section is slid when applying the same to the receptacle, dogs carried on said flange extensions, said wall having oppositely disposed sockets receiving said dogs for latching the body section to the receptacle, and a movable cover section carried by the body section.
5. In a covered receptacle, the combination of a receptacle body having an upper opening with a wall extending around the said opening, a cover having a body section capable of being slid laterally over the edge of the wall at one side of the receptacle so as to cover a part of the said opening, said body section having a marginal flange including side extensions lying substantially parallel with the direction in which the body section is slid when applying the same to the receptacle, dogs in the form of pins carried respectively of the flange extensions, said wall having sockets receiving said pins for latching the body section to the receptacle, and a movable cover section pivotally mounted on said pins.
6. In a covered receptacle, the combination of a receptacle body having an upper opening with a wall extending around the said opening, a cover having a body section capable of being slid laterally over the edge of the wall at one side of the receptacle so as to cover a part of the said opening, said body section having a marginal flange including side extensions lying substantially parallel with the direction in which the body section is slid when applying the same to the receptacle, dogs carried respectively on said flange extensions, said wall having oppositely disposed sockets receiving said dogs for latching the body section to the receptacle, a movable cover section carried by the body section, and means associated with the dogs for resiliently pressing the same into the sockets.
7. In a covered receptacle, the combination of a receptacle body having an upper opening with a wall extending around the said opening, a cover having a body section capable of being slid laterally over the edge of the wall at one side of the receptacle so as to cover a part of the said opening, said body section having a marginal flange including side extensions lying substantially parallel with the direction in which the body section is slid when applying the same to the receptacle, and including a transverse extension, dogs carried on the side extensions and projecting toward the wall and means on the wall for cooperating with the dogs to latch the body section to the same.
8. In a covered receptacle, the combination of a receptacle body having an upper opening with a wall extending around the said opening, a cover having a body section capable of being slid laterally over the edge of the wall at one side of the receptacle so as to cover a part of the said opening, said body section having a marginal flange including side extensions lying substantially parallel with the direction in which the body section is slid when applying the same to the receptacle, and including an end extension, a dog carried by each side extension of the flange, a spring mounted on the flange with means for urging the dogs inwardly toward the wall, said wall having sockets to receive the said dogs, and cooperating with the same to latch the body section to the receptacle.
9. In a covered receptacle, the combination of a receptacle body having an upper opening with a wall extending around the said opening, a cover having a body section capable of being slid laterally over the edge of the wall at one side of the receptacle so as to cover a part of the said opening, said body section having a marginal flange including side extensions lying substantially parallel with the direction in which the body section is slid when applying the same to the receptacle, and including an end extension, a dog carried by each side extension of the flange, a spring mounted on the flange with means for urging the dogs inwardly toward the wall, said wall having sockets to receive the said dogs, and cooperating with the same to latch the body section to the receptacle, said wall further having guide grooves on its outer face for guiding the dogs into the sockets when the body section is slid into position.
10. In a covered receptacle, the combination of a receptacle body having an upper opening with a wall extending around the said opening, a cover having a body section capable of being slid laterally over the edge of the wall at one side of the receptacle so as to cover a part of the said opening, said body section having a marginal flange including

side extensions lying substantially parallel with the direction in which the body section is slid when applying the same to the receptacle and including an end extension, a spring attached to said end extension of the flange and having arms extending along the side extensions of the flange, a dog associated with each side extension and urged inwardly by its corresponding spring arm, said wall having sockets to receive the said dogs, and cooperating with the same to latch the body section to the receptacle.

11. In a covered receptacle, the combination of a receptacle body having an upper opening with a wall extending around the said opening, a cover having a body section capable of being slid laterally over the edge of the wall at one side of the receptacle so as to cover a part of the said opening, said body section having a marginal flange including side extensions lying substantially parallel with the direction in which the body section is slid when applying the same to the receptacle and including an end extension, a spring attached to said end extension of the flange and having arms extending along the side extensions of the flange, a dog associated with each side extension and urged inwardly by its corresponding spring arm, said wall having sockets to receive the said dogs and cooperating with the same to latch the body section to the receptacle, the end wall of said receptacle having a socket therein, and said end flange having means for engaging the same to lock down the end portion of the body section.

12. In a covered receptacle, the combination of a receptacle body having an upper opening with a wall extending around the said opening, a cover having a body section capable of being slid laterally over the edge of the wall at one side of the receptacle so as to cover a part of the said opening, said body section having a marginal flange including side extensions lying substantially parallel with the direction in which the body section is slid when applying the same to the receptacle, and including an end extension, a spring on the inner side of the end extension of the flange, a pin on the end extension securing the spring to the same and projecting at its inner side toward the end wall of the receptacle, said spring having side arms extending along the inner sides of the side extensions of the flange, a latching pin mounted at each side flange and urged inwardly toward the wall by the corresponding spring arm, said wall having oppositely disposed sockets receiving the side pins and having a socket receiving the first named pin, and cooperating to latch the body section to the receptacle.

13. In a covered receptacle, the combination of a receptacle body having an upper opening with a wall extending around the said opening, two opposite side walls of said

receptacle adjacent the opening having sockets formed respectively in the same, and one of the transverse walls of the receptacle having a socket formed therein adjacent its upper edge, and a cover section having a flange with means for interlocking with the last named socket and having means for yieldingly engaging in the said first named sockets.

Signed at Los Angeles, Cal., this 8th day of June, 1931.

WALTER J. VAN ROSSEM.
